UNITED STATES PATENT OFFICE.

JOHN C. CROMWELL, OF CLEVELAND, OHIO, ASSIGNOR TO THE GARRETT-CROMWELL ENGINEERING COMPANY, OF CLEVELAND, OHIO, A CORPORATION OF OHIO.

ТИЛТИНГ ФУРНАС.

No. 823,669.

Specification of Letters Patent.

Patented June 19, 1906.

Application filed April 9, 1906. Serial No. 310,624.

To all whom it may concern:

Be it known that I, JOHN C. CROMWELL, a citizen of the United States, residing at Cleveland, in the county of Cuyahoga and State of Ohio, have invented a certain new and useful Improvement in Tilting Furnaces, of which the following is a full, clear, and exact description.

The object of the present invention is to provide an improved construction for tilting furnaces, which is especially applicable to furnaces of the open-hearth type, which receive their gas and air supply from the ends, but it is also of utility in connection with any tilting metallurgical furnace which is designed to hold large masses of material and to be subjected to high temperature.

The problem of mounting tilting metallurgical furnaces has been approached from several sides and various solutions have been suggested, each possessed of certain advantages, but also characterized by certain defects which are well known to those familiar with the practice in this art.

One of the most familiar types of tilting furnace is that which is provided with a curved bearing at each end of the bottom of the furnace, the bearing being curved on a radius drawn from a point about the center of the gas-ports. The furnace is supported by a series of rollers journaled upon a supporting-base in a curved line corresponding to the curvature of the furnace-bearing, so that the tipping of the furnace would be accomplished by causing it to rotate upon the said rollers. This style of furnace is exceedingly defective by reason of the fact that the curvature of the base constantly changes owing to the expansion caused by the heat, with the result that the furnace-bearings will be at times supported by only two of the rollers and the weight and strains thus concentrated at points of the furnace and supporting-base, which were not contemplated in the original design. Subsequent to the use of this type there was adopted a floating cradle composed of a series of rollers held together by curved rails in which they are journaled interposed between the curved bottom of the furnace

and the curved top of the supporting-foundation. This type of support is also subject to the above-described trouble, arising from expansion of the furnace when heated, in that

the furnace-bearing is altered, and therefore concentrates its load upon only a few of the rollers of the floating cradle, thus distributing the strains along lines which cannot be properly allowed for in advance. Furthermore, these cradles are intended to slip and slide between the furnace and the supporting-foundation, but do not always move back and forth to the same extent, with the result that one is sometimes so far ahead of the other in its relative position that the one end of the furnace has to be jacked up, while the cradles are replaced in alinement with each other. A third old type of furnace known in the art is mounted on a supporting-frame beneath the base of the furnace, which frame has curved rockers at each end, each rotating on a pair of rollers journaled in a horizontal line on the top of a flat supporting-base. The ends of the curved rockers extend considerably beyond the bottom of the furnace in order to allow for the proper rotation, but such extensions are, as will be obvious, subjected to a great breaking strain when the furnace is tilted, so that the load is thrown thereon. Furthermore, these projections are quite awkward, being obviously in the way. Still another type of furnace is the type which rolls forward as it tilts and which, as distinguished from those previously mentioned, is provided with a curved base resting directly upon a horizontal foundation upon which it rolls back and forth, thus causing the entire furnace to move forward as it is tilted. This type is particularly objectionable by reason of it being necessary to roll it so far forward when the material is low that the gas-ports will pass entirely out of register with the conduit leading from the regenerator and even raised to the points where cold air from the outside rushes in and chills the furnace. Obviously no combustion can take place under these conditions. The manner in which I have mounted my tilting furnace is possessed of all of the advantages of the first three types which rotate about a definite center and is also possessed of the advantages of the last type in that there is no variation or shifting in the strains during use.

Referring to the accompanying drawings, Figure 1 is a section, partly diagrammatic, taken about midway of the furnace looking toward one end, as along line 1 1, Fig. 2. Fig.

2 represents a longitudinal section of one end of the furnace, showing certain parts in elevation. Fig. 3 is a detail of a bearing-wheel mounted upon the trackway. Fig. 4 is a view similar to Fig. 2 of a modified support.

The furnace A is of the usual construction of the open-hearth type, having communication with the gas and air ports B B, leading from the regenerators, and is mounted upon a framework of girders C, suitably designed and proportioned to withstand the supporting strains in all positions in which the furnace may be tilted. The girder-frame has at each end supporting-brackets C', in which are journaled rollers C², adapted to ride upon the curved trackway D of the supporting-foundation. The curvature of this trackway is that of a circle having its center about the gas and air ports aforesaid. It will be noted that this trackway has, beside the bearing or rolling surface upon which the supporting-rollers move, also a segmental rack D' of proper length designed for use in connection with a motor mechanism upon the end of the furnace for the purpose of tilting the same. The motor employed for this purpose is of any suitable type, but preferably electric, and is swung in any convenient manner. I have shown the driving connection as that of a worm-shaft E' and wheel E², transmitting power from the motor E to gears E³ E³, which turn transmit the power to a cog E⁴, meshing with the segmental rack D' before mentioned. This reduction device is very efficient for the purpose intended, and the furnace is under absolutely perfect and positive control in all positions. This furnace may obviously be rotated about a given axis, which will be the line passing through the centers of curvature of the two supporting-rails, and it is so designed that the shifting of the bath upon tilting will not disturb the state of stable equilibrium, the center of gravity being close to the axis of rotation. During rotation the fuel-ports will not be exposed to the cold air, and combustion may be continued at all positions of the furnace. It will be further noted that no matter how the furnace may expand under the influence of heat the supporting-frame upon which it is mounted will always receive the thrusts along exactly the same lines, so that the original design will be effective and not disclose weakness under the changed conditions.

In conformance with the principle above set forth I have produced a modified supporting structure, differing as to certain specific details, which is illustrated in Fig. 4. In this form I have journaled short equalizing-beams F instead of bearing-wheels in the ends of the furnace-frame C and have journaled wheels F' in each end of the said beams. Each beam and its wheels go to make up a single support which as a unit is journaled in

the end of the frame. It will be plain that the same principle obtains in this structure which is embodied in the form first described, since the expansion of the furnace due to heat will not alter the points of bearing or direction of thrust in any manner, and the frame will always bear the load exactly as it was designed to do. An advantage of this modified structure lies in the fact that a greater number of bearing-wheels may be employed, and, in the case of the exceedingly large furnaces which I am enabled to produce from the broad principle of construction previously outlined, this is a matter of great importance, since the crushing effect is distributed among the several wheels which go to make up the individual supports. I have thus, owing to the maintenance of the conditions for which the furnace was designed, been enabled to construct furnaces of great dimensions with absolute certainty that they will hold together at all points in all positions. It is thought that with the combination of these advantages in one structure the problem of constructing heavy tilting furnaces has been satisfactorily solved in a manner which will permit of practically unlimited expansion in the way of an increase in size of open-hearth furnaces, which is in the present condition of the art of the greatest moment.

Having thus described my invention, I claim—

1. In combination, a tilting metallurgical furnace having a frame, a curved supporting-trackway for the furnace, each end of the furnace having journaled therein two supports which bear on said trackway.

2. In combination, a furnace adapted to rotate about a given axis having a frame having two supports journaled at each end, a supporting-base having a fixed curved runway upon which said supports bear, and motor mechanism mounted on the furnace and adapted to rotate the same.

3. In combination, a tilting metallurgical furnace having a frame, a curved supporting-trackway for the furnace, each end of the furnace having journaled therein two equalizing-beams which have two rollers journaled thereon and bearing on the trackway.

4. In combination, a tilting furnace, a curved trackway for the furnace, each end of the furnace having supports mounted thereon and riding upon said trackway in such manner as to be independent in their supporting function of the expansion of the furnace.

In testimony whereof I hereunto affix my signature in the presence of two witnesses.

JOHN C. CROMWELL.
